(57) **CLAIM**

I claim the ornamental design for a display hanger, as shown and described.

DESCRIPTION

FIG. 1 is a perspective view of the display hanger highlighting a circular embossment projecting above a top surface of the display hanger;

FIG. 2 is a top view of the display hanger of FIG. 1;

FIG. 3 is a bottom view of the display hanger of FIG. 1;

FIG. 4 is a back view of the display hanger of FIG. 1;

FIG. 5 is a front view of the of FIG. 1;

FIG. 6 is a side view of the display hanger of FIG. 1; and,

FIG. 7 is a side view of the display hanger of FIG. 1 showing the side opposite that shown in FIG. 6.

The broken lines in the drawing depict environmental subject matter only and form no part of the claimed design.
